UNITED STATES PATENT OFFICE.

FRANK DUTCHER, OF GROTTES, VIRGINIA.

WINDOW CONSTRUCTION.

1,281,312.

Specification of Letters Patent. Patented Oct. 15, 1918.

Application filed August 30, 1916. Serial No. 117,675.

To all whom it may concern:

Be it known that I, FRANK DUTCHER, a citizen of the United States, residing at Grottoes, in the county of Rockingham and 5 State of Virginia, have invented certain new and useful Improvements in Window Constructions, of which the following is a specification, reference being had to the accompanying drawings.

10 This invention has for its primary object to provide a simple and novel arrangement and mounting of the window sashes whereby the necessity of employing the usual sash weights may be avoided.

15 It is another object of the invention to provide hingedly connected sashes slidably mounted at one of their ends in the window frame, and means operatively connecting and balancing the hinged sashes and operating to sustain the same in their adjusted 20 open positions.

25 It is also an important object of my invention to provide simple and effective operating means whereby a plurality of pairs of hinged sashes may be easily operated in unison and moved to their open or closed 30 positions.

35 It is a further general object of the invention to improve the construction and service-ability of windows whereby the desired amount of ventilation may be obtained, the window construction being comparatively simple, durable and capable of manufacture at relatively low cost.

40 With the above and other objects in view, my invention consists in the novel features of construction, combination and arrangement of parts to be hereinafter more fully described, claimed and illustrated in the accompanying drawings, in which,

Figure 1 is a vertical sectional view showing two pairs of window sashes disposed in their closed positions within the frame;

Fig. 2 is a similar view showing the sashes 45 open;

Fig. 3 is a view similar to Fig. 1, illustrating a slightly modified construction;

Fig. 4 is a perspective view showing still another operating means for the sashes;

50 Fig. 5 is a similar view of a still further modification;

Fig. 6 is a horizontal sectional view through one side of the window, illustrating

the mounting of the sliding ends of the window sashes; and

Fig. 7 is a similar view illustrating a sheet metal, fire-proof construction of the window.

Referring more particularly to Figs. 1 and 2 of the drawings, 5 designates the frame of the window, the vertical side bars 6 of which are provided in their inner faces with the longitudinal channels 7. Within the frame 5, the sashes are arranged in pairs. The sashes 8 in each pair are hingedly connected to each other at their opposed ends, as at 9. At the opposite ends of the top rail of the upper sash and the bottom rail of the lower sash in each pair, trunnions 10 are rigidly fixed in any preferred manner. In Fig. 6 of the drawings, I have illustrated one convenient practical manner of mounting the sashes for relative sliding movement in the window frame. To this end, the metal blocks 11 are mounted in the channels 7 for free vertical movement, and each of said blocks is formed with a bearing socket 12 to receive one of the trunnions 10.

In the top bar of the frame 5, at each end thereof, a pulley or sheave 13 is suitably mounted, and over the same a chain or cord 14 is trained. One end of this chain is suitably connected to the slide block 11 for the upper sash 8. The chains 14 extend downwardly and around and between the pair of guide pulleys 15 and have their lower ends attached to the slide blocks 11 for the trunnions of the lower sash 8 in the upper pair of sashes. The chains 14 are entirely covered and hidden from view by the molding 90 strips 16 which are secured to the inner faces of the side bars of the frame 5.

To the slidably mounted end of each of the sashes 8 and preferably at each side of the sash, a bracket member 17 is secured. To the brackets on the corresponding sashes of the two pairs, the ends of the vertical bars 18 are pivotally connected so that in the relative movement of the sashes in the upper pair, through the medium of the chain 14 a corresponding relative movement is transmitted to the sashes in the lower pair.

The operation of the above described embodiment of my invention will be readily understood. Assuming that the several 105 sashes are in their closed positions as shown

in Fig. 1, an outward pressure upon the hingedly connected ends of the sashes in the upper pair causes the chains 14 to pull the sliding end of the lower sash upwardly 5 to the same extent as the sliding end of the upper sash moves downwardly in the window frame, and the tendency of the inner end of the upper sash to gravitate downwardly in the window frame is counterbalanced by the weight of the lower sash. The 10 corresponding sashes in the two pairs being connected by the bars 18, it is manifest that the sashes in the lower pair will also be moved to precisely the same relative angular 15 relation as the sashes in the upper pair. Thus, any desired amount of ventilation may be obtained and the angular disposition of the several sashes operates to direct the air currents into the room or apartment.

20 In Fig. 3 of the drawing, I have illustrated a slightly different chain connection between the sashes, whereby the connecting bars 18 may be dispensed with. In this arrangement, the chains 14' extend substantially the entire length of the window and have their upper ends attached to the slide blocks of the uppermost sash and their lower ends to the slide blocks of the lowermost sash. The intermediate portions of 25 the chains pass between the guide rollers or pulleys 15' which are mounted substantially at the center of the window frame. The lower sash in the upper pair is connected to the upper sash in the lower pair 30 by means of the hinges 9', it being understood that these hingedly connected ends of the two pairs of sashes are not slidable in the side bars of the window frame but are freely movable transversely with respect 35 thereto. Thus, the four sashes may be disposed in various angularly adjusted positions or moved in unison vertically in the window frame and will be sustained in such 40 adjusted positions by means of the counterbalancing chains 14'.

Fig. 4 illustrates still another alternative arrangement of the operating connection between the window sashes wherein the corresponding sashes in each pair are connected 50 at one side of the window by the bars 18', and to the upper ends of the bars connecting the lower sashes, chains 14^a are attached and extend upwardly around guide pulleys 13' mounted on the top bar of the window frame 55 and then across to the opposite side of the frame and around similar pulleys, and have their other ends attached to the respective sashes in the upper pair. The sashes are operated and counterbalanced by means of 60 the chain connections in identically the same manner as heretofore described.

Fig. 5 illustrates a somewhat simplified connection between the several sashes wherein a single vertical bar 18^a is arranged at 65 each side of the window and connects the

corresponding sashes. To the corresponding end of each of said bars, one end of a cord or chain 14^b is attached and engaged around a guide pulley 13^a at the top of the window frame, and then extended immediately downward, one of said chains being attached to a bracket plate 19 on the lower sash in the upper pair and the other chain attached to a similar bracket on the upper sash. For the purpose of affording a clear 70 understanding of my invention, I have shown in these latter figures the operating connection between the several sashes entirely exposed, but it is manifest, of course, that in practice, these parts may be suitably mounted in the window frame or enclosed within a suitable casing or housing fixed thereto. It is further to be borne in mind that while I have herein illustrated only two pairs of the relatively movable sashes, any 75 desired number of pairs may be used, the 80 sash connections simply being multiplied.

The construction of the window as shown in Fig. 6, is quite similar to the usual construction of wood windows, but in Fig. 7 I 90 have shown the manner of mounting the sliding sashes in a metal, fire-proof window construction, and it will be noted therein that the vertical side of the window frame is constructed in two parts, each formed from a 95 sheet metal plate. The main section 20 is bent to provide the vertical channel 7' in its inner wall, within which the slide block 11' is mounted to receive the pin or trunnion 10' on the sash 8'. The frame plate 20 is also bent to provide a vertical flange 21 at one side of the channel 7', and the sheet metal plate from which the vertical stile of the window sash 8' is formed, is suitably bent to provide an oppositely projecting, vertical flange 22 which extends inwardly between the flange 21 and the inner side face of the frame plate 20. The flange 22 in Fig. 8, and the corresponding part in Fig. 7, does not extend the entire length of 105 the sash, but terminates short of the sash pivot so that said flange will not bind against the sash frame and prevent the free 110 swinging movement of the sash. A longitudinally extending, sheet metal channel 115 plate 23 projects inwardly from the wall of the channel 7' and is suitably secured to the opposite sides thereof. The spaced, intermediate portions of the guide channels 7' and the plate 23 provide a pocket or chamber 120 to receive the chain connection between the sashes. The edges of the body plate 20 on the sash frame are connected by the outer vertical side plate 25 by forming interlocking, longitudinal tongues on the edges of 125 said plates and securely clenching the same together.

From the foregoing description, taken in connection with the accompanying drawings, the construction, manner of operation and 130

several advantages of the illustrated embodiments of my invention will be clearly and fully understood. In practice, I have found that the construction and mounting of the 5 sashes above referred to provide a very convenient and easily operated window whereby the adjustment of the sashes can be readily effected to secure the desired ventilation. The convenience of this arrangement of the sashes whereby they can be disposed at various relative inclinations in washing or cleaning the windows, is apparent. In the present application, no particular mounting and construction of the 10 15 guide pulleys or wheels for the cord or chain connection is included, as this and other details of the invention I propose to later improve whereby a practical, efficient and durable construction of such parts will be provided. It is, therefore, to be understood that in the commercial development of the invention, I contemplate making numerous mechanical changes of a minor character and I, therefore, reserve the privilege of adopting 20 25 all such legitimate modifications as may be fairly embodied within the spirit and scope of the invention as claimed.

Having thus fully described my invention, what I desire to claim and secure by 30 Letters Patent is:—

1. The combination with a window frame, of a pair of sashes hingedly connected to each other at one of their ends, means for slidably mounting the other ends of the 35 sashes in the window frame for relative vertical movement, an additional pair of relatively movable sashes, means operatively

connecting each of the latter sashes to one of the first named sashes and permitting of the angular movement of all of said sashes with respect to each other, and counterbalancing means connected only to the first named sashes to sustain the several sashes in their adjusted positions with respect to the frame. 40 45

2. The combination with a window frame, of upper and lower pairs of sashes operatively connected to each other for movement as a unit, the sashes in each pair being also hingedly connected to each other for relative angular adjustment, and counterbalancing means movable in the frame and operatively connected to certain of the sashes to sustain the sashes in their adjusted angular positions and also prevent their casual vertical movement with respect to the frame. 50 55

3. The combination with a window frame, of a plurality of pairs of window sashes, the sashes in each pair being hingedly connected to each other at one of their ends, means 60 for slidably mounting the sashes at their other ends in the window frame for relative vertical movement, an operating connection between the corresponding sashes in the several pairs, and means for balancing said sashes and sustaining the same in their angularly adjusted positions in the frame with respect to each other. 65

In testimony whereof I hereunto affix my signature in the presence of two witnesses.

FRANK DUTCHER.
